UNITED STATES PATENT OFFICE.

JULIUS L. BENDER, OF CHARLOTTE, NORTH CAROLINA.

SHOE-POLISHING STAND.

Application filed March 24, 1921. Serial No. 455,263.

To all whom it may concern:

Be it known that I, JULIUS L. BENDER, a citizen of the United States, residing at Charlotte, in the county of Mecklenburg and State of North Carolina, have invented certain new and useful Improvements in Shoe-Polishing Stands, of which the following is a specification.

This invention relates to a foot rest or support, and particularly to such a device having adjustable guides for a polishing band or cloth designed to effect the efficient rubbing of toe, body and heel of the shoe.

An object of the invention is to provide such a stand or support with a pair of guides for the rubbing or polishing cloth or band, which can be set in one position to secure an efficient polishing of the toe portion of the shoe and in an alternative position to secure an efficient polishing of the heel portion of the shoe, portions of the body of the shoe being polished in both positions of the guides. Another object of the invention is to provide a stand of this type with yielding or adjustable guides or band supporting elements, by means of which various widths of shoes may be polished with equal facility, the guides yielding under the influence of the band to assume the proper position for the particular shoe being polished. A further object of the invention is the provision of a maximum bearing for the pivot ends of such guides, designed to produce a strong and rigid construction.

Other objects and advantages of the invention will hereinafter appear in the following description and the novel features thereof will be particularly pointed out in the appended claims.

In the drawings, in which like reference characters indicate like parts throughout the several figures,

Figure 1 is a side elevation of the shoe rest or support comprising my invention with the guides horizontally disposed and in position to support the polishing band when acting upon the toe portion of the shoe,

Figure 2 is a similar view showing the guides in an upright or inclined position supporting the band in the act of polishing the heel portion of the shoe,

Figure 3 is a plan of the shoe rest or support,

Figure 4 is a front elevation thereof, and

Figure 5 is a section through the support or stand showing the method of pivotally

mounting the guides within the block or base.

Referring to the drawings, the numeral 9 represents a shoe which is presumed to be upon the foot of a wearer, and 10 a polishing band or cloth, while 11 represents the stand, support or rest therefor while polishing the shoe. 12 designates the base of the stand which is in the form of a block of any suitable material, preferably light, such as aluminum or wood.

Pivoted in this block in a manner hereinafter to be described are the guides, which are in the form of stout wire stock, upon which are mounted sleeve members 15 for the purpose of reducing the friction of the band or cloth pulled or drawn around the guides in the operation of polishing the shoe. The guides 13 and 14 have two positions while in use, that shown in Figure 1, which may be called their horizontal position, is for use when the toe and adjacent body portion of the shoe is to be polished, while that shown in Figure 2, which may be called their upright position, is for use when the heel and adjacent body portion of the shoe are to be polished.

The base or block of the stand is provided with two bores, best shown in Figure 5, in which are mounted the bearing sleeves 16 and 17, receiving the bent or pivot ends 18 and 19 of the guides. These pivot ends are provided with enlargements or lugs 20 and 21, which act as limiting stops in connection with the slots 22 and 23 in the sleeves 16 and 17. The bearing sleeves are securely held within the block or base by means of straps 24 and 25, preferably of sheet metal, attached to the sides of the block or base and provided with openings sufficiently large to permit the free and easy movement of the guide ends therein but of a size to retain the sleeve within the bore. These straps are also formed with hooks 26 and 27 for a purpose to be hereinafter explained.

It will be noted that the bearing sleeves 16 and 17 are extended the full width of the base 12 and are superposed upon each other, and that the locking lug and slot are located at the ends of the guide and sleeve respectively. While these features secure desirable results, it will be understood that the details of construction may be altered in these and other particulars without departing from the spirit of the invention.

At the front portion of the block or base

there is mounted a holding plate designated by the numeral 28. It is of a width greater than the width of the block 12, and beyond the edges of the block, there is formed in the plate two L-shaped slots designed to receive and hold in position the hooked ends 29 and 30 of the guides, and it will be noted that the horizontal portions of said slots are of sufficient length to permit of a considerable movement of the hooked ends, corresponding in degree to the movement permitted the lugs 20 and 21 in the slots 22 and 23 of the bearing sleeves 16 and 17.

Pivottally mounted at the forward lower end of the block or base are guide-supports 31 and 32, which in their inactive position lie in the hooks 26 and 27 of the straps 24 and 25, as best seen in Figures 1 and 5. As shown in Figure 2, these guide-supports in their active or useful position receive in apertures in their free ends the hooked ends 29 and 30 of the guides, thereby supporting the said guides in their upright or inclined position for use in polishing the heel and adjacent body portion of the shoe. The length of the hooked ends permits a certain freedom of movement of the guides with relation to the guide-supports comparable with that permitted the lugs 20 and 21 within the bearing sleeves 16 and 17.

Whether the guides are in their horizontal or upright position, it will be seen that they are adjustable toward and from each other to permit of their efficient use with a band or fabric in polishing either a narrow or a wide shoe. In order, however, that the guides may be normally in their closest relationship to each other, resilient means are provided for holding them. An illustrative means of this type is shown in Figure 3 wherein an extension is formed upon the guide, and this extension is connected to the block by means of a spring, said spring being secured to the guide and block, respectively, in any suitable manner.

The use and operation of the device will be generally understood from the foregoing description, but a detailed recital of the same will now be given.

The parts of the stand are assembled as shown in Figures 1 and 3, the band or cloth 10 being placed over the top of the block or base 12 and under the guides 16 and 17. The shoe upon the foot of the wearer is then placed upon the block with the heel abutting the rear face thereof, and the toe extended under that portion of the band lying upon the upper face of the block or base. Pulling alternatively upon the ends of the band and a sliding of the same along the guides will accomplish the necessary rubbing action required for the polishing of the shoe at the toe thereof and the adjacent body portion of the shoe. It will be seen that if a relatively narrow shoe is being

polished that the guides will remain in their normal position, relatively close together, whereas if a shoe, relatively wide, is being polished the guides will spread apart under the pulling action upon the band, the lug and slot engagement of the guides with the bearing sleeves permitting this spreading at one end while the slot and hooked end engagement of the locking plate and guides will permit this spreading at the opposite end. Upon release of the pulling action the springs 34 will return the guides to their relatively close position.

When it is desired to rub or polish the heel and adjacent body portion of the shoe the forward hooked ends of the guides are removed from the locking plate at the front of the stand or support and swung upwardly to an inclined position; the guide-supports 31 and 32 are also swung upwardly to an inclined position, when the hooked ends 29 and 30 are engaged with the apertures in the free ends of the guide-supports. This position of the parts is illustrated in Figure 2 of the drawing. The heel of the shoe is then placed within the loop formed in the band or cloth and caused to abut the end of the block as heretofore. In this position of the parts a pulling action upon the ends of the band, alternately, will cause the necessary rubbing or polishing of the heel and adjacent portions of the shoe.

It will be seen that by my invention a stand or support having a single pair of band guides is provided, and by reason of their capability of adjustment, these guides perform the functions of both longitudinal and upright fixed guides. It will be also apparent that with my invention a minimum width of block can be used without destroying the utility of the device for shoes of extra wide lasts. These and other objects are accomplished by the details of my invention, which however may be varied considerably without departing from the spirit thereof as defined by the appended claims, the specific embodiment of the invention disclosed being merely indicative. The band or cloth which I prefer to use is doctored with a chemical to promote ease of operation and a better polish. Such a substance may be indicated by wax.

Having described my invention, what I claim as new and desire to secure by Letters Patent is:

1. In a polishing device, a shoe rest, a pair of pivotally mounted guides for a polishing band or cloth, means at the forward end of said shoe rest for holding said guides in a horizontal position for toe polishing, and means mounted upon said shoe rest for holding said guides in a raised position for heel polishing.

2. In a polishing device, a shoe rest, a pair of guides for a polishing band or cloth piv-

totally mounted at the rear end of said shoe rest, a locking plate at the front end of said shoe rest for holding said guides in a horizontal position for toe polishing, and guide-supports pivotally mounted upon said shoe rest for holding said guides in a raised position for heel polishing.

3. In a polishing device, a shoe rest, a pair of guides for a polishing band or cloth pivotally mounted at one end of said shoe rest, and a locking plate at the other end of said shoe rest provided with L-shaped slots in which the free ends of said guides are held while the parts are assembled for toe polishing.

4. In a polishing device, a shoe rest, a pair of guides for a polishing band or cloth pivotally mounted at one end of said shoe rest, and guide-supports pivoted at the opposite end of said shoe rest and provided with apertures at their free ends in which the free ends of the guides are held when the parts are assembled for heel polishing.

5. In a polishing device, a shoe rest provided with a pair of bores, a pair of guides for a polishing band or cloth comprising straight members having bent ends mounted in said bores, means for retaining said pivot ends in said bores, and means for holding the free ends of the guides in fixed relation to said shoe rest.

6. In a polishing device, a foot rest provided with a transverse bore, a guide for a polishing band or cloth comprising a bent end yieldingly mounted in said bore, and means for maintaining said end in said bore.

7. In a polishing device, a foot rest provided with a transverse bore, a bearing sleeve in said bore, a longitudinal guide for a polishing band or cloth comprising an angularly arranged pivot end mounted in said sleeve, and means for adjustably mounting said pivot end within said bearing sleeve comprising a lug and slot connection between said parts.

8. In a polishing device, a foot rest, a pair of guides for a polishing band or cloth pivotally mounted in said foot rest, means for maintaining said pivotal connection between the parts comprising straps having at their lower ends hooks, a locking plate at the forward end of said foot rest for holding the free ends of said guides when arranged in a horizontal position, and guide-supports pivotally mounted upon said foot rest and having their free ends resting normally in said strap hooks and provided with means for holding said guides when arranged in a raised position.

In testimony whereof I affix my signature.

JULIUS L. BENDER.
